Patented Mar. 18, 1913.

UNITED STATES PATENT OFFICE.

HENRY ARMSTRONG, OF BROOKLYN, NEW YORK, ASSIGNEE TO MERGEN-
THALER LINOTYPE COMPANY, A CORPORATION OF NEW YORK.

LINNE-CASING MACHINE.

1,058,814.

Specification of Letters Patent. Patented Mar. 18, 1913.

Application filed June 18, 1910. Serial No. 587,710.

To all whom it may concern:

Be it known that I, HENRY A. ARMSTRONG, of the borough of Brooklyn, county of Kings, and State of New York, have invented 5 a new and useful improvement in Line-Casting Machines, of which the following is a specification.

My invention has reference to line casting machines of the character represented 10 in Letters Patent of the United States No. 438,532, wherein circulating matrices and circulating double wedge spacers or justifiers, stored in magazines, are released individually by finger keys, assembled temporarily in line, and the line presented momentarily to close the face of a slotted mold and form type characters on the edge of the printing slug or linotype cast therein, the line being thereafter transferred to distributing devices, by which the matrices and 15 spacers are returned to their magazines. In the machines as heretofore constructed the spacers, each consisting of two oppositely tapered wedges permanently united by a vertical sliding joint, are stored at a considerable distance above the level at which the lines are composed. When the keys are manipulated by very rapid operators there is danger of the spacers and matrices being 20 transposed; as for instance, danger of a spacer entering the line in advance of a previously released matrix instead of behind it. My invention is designed to prevent this and similar occurrences.

To this end, it consists in means whereby the spacers are delivered one at a time from their magazine, necessarily remote from the composing point, and arrested and held in reserve at a point near the matrix line, so 25 that when released by the finger key they may reach the line quickly and by a short movement—the parts being so arranged that the delivery of one spacer to the line is followed by the delivery of its successor from 30 the magazine to the point of detention when the space key is next depressed, and also in connecting the said secondary releasing device with the finger key mechanism by which the matrices are released, so that when a key 35 is depressed to deliver a matrix to the line it will at the same time release a spacer, which latter being close to the line will be sure to enter the same in advance of the next matrix.

I have limited the drawings herein to

those parts of the ordinary commercial Mergenthaler linotype machine with which my invention is immediately associated. It is to be understood that as to all other parts the machine may be of the ordinary or any suitable construction.

Referring to the drawings, the figure is a perspective view illustrating in outline the spacer magazine, the assembling elevator in which the line is composed, and devices for releasing the matrices and spacers.

In the drawings, A represents the inclined channeled magazine in which the matrices B are stored as usual.

C represents one of the series of escape- 70 ments for releasing the matrices from the magazine channels.

D represents the vertical escapement-actuating reeds, one for each escapement.

E are the reed actuating yokes mounted 75 one below each reed, each yoke containing a lifting cam F arranged to contact with and ride upon a continuously rotating roll G.

H are finger keys representing the various characters etc.

I are vertical bars through which the angular yoke sustaining dogs J are actuated and the yokes E permitted to descend in order that their cams may contact with the driving roll, so that when a key is actuated 85 an escapement, C, is moved and a matrix released for delivery to the line in the course of composition in the manner fully explained in Letters Patent of the United States No. 530,931.

J is a stationary magazine in which the spacers or justifiers, K, are suspended. These spacers are similar to those represented in Letters Patent of the United States No. 438,532, the shorter wedge having on its upper end lateral ears L by which they are suspended on the inclined side rails of the magazine.

L is one of a pair of vertical slides by which the spacers are lifted clear of the 100 detaining shoulders L' in the magazine and permitted to fall through a chute or channel, M, to the line in the course of composition.

N is the assembling elevator, so-called, 105 having in its top a horizontal channel to which the matrices and spacers are successively delivered, and in which they are composed side by side in a horizontal line.

O is a centrally pivoted lever mounted 110

in the main-frame, with one end connected to the spacer delivering slides L, and the opposite end connected to the vertical reed P, which receives its motion through a cam yoke mechanism and finger key, R, identical with those employed for actuating the matrix escapements C so that when the key R is depressed the slides L will deliver a spacer from the magazine.

10 So far as described, the parts may be of the ordinary construction; well understood by those skilled in the art.

In carrying my invention into effect I provide a stop finger Q, mounted on a rock shaft q, and arranged in the path of the descending spacers, so that after each spacer is released from the magazine it will be arrested by the stop Q in the position shown in the drawings, with its lower end a short 20 distance above the level at which the matrices are composed. The shaft q is provided with a rocking arm q', connected by a link q² to a rocker frame q³, which is mounted to turn on a stationary horizontal 25 axis q⁴. This frame extends entirely across the keyboard and its forward end is arranged to enter notches q⁵ in all the reeds D and P by which the matrix-releasing devices are actuated. When the spacer key 30 R is actuated the reed P is lifted, and the slides L caused to deliver a spacer from the magazine J, the spacer descending until it is arrested by the stop Q, immediately 35 above the line. When the key H, representing a matrix, is actuated the corresponding reed D rises and actuates the matrix escapement C and also, at the same time, lifts the frame q³, causing the stop Q to be withdrawn, so that the spacer sustained thereby 40 near the line may drop into the line in advance of the matrix. Thus it will be seen that the spacer key R causes a spacer to assume a position close to the line while a letter key releases the previously arrested 45 spacer and also releases the matrix, the spacer, by reason of its location, entering the line before the arrival of the matrix.

My invention consists in means whereby the spacers are delivered from the distant 50 magazine to the matrix line by two distinct movements; first from the magazine to a position of rest near the line; and second from said position to the line—the first movement taking place in advance of the 55 time that the space is called for in the line.

It also consists, broadly, in combining with the finger key, mechanism which serves to release a spacer that it may pass to the line and also to release a matrix that it 60 may also enter the line.

While the mechanism shown and described is a practical one for the purpose, it will be understood by the skilled mechanic that the parts may be widely modified as 65 to form an arrangement without changing

their principle of action, or passing beyond the limits of my invention.

The first part of my invention, namely, the means whereby the spacers are delivered by two distinct movements, is shown herein 70 as applied specifically to mechanism whereby the spacer is prevented from reaching the line before a previously released matrix. Its adaptability to other mechanisms and its use for other purposes will be obvious. 75 Thus, for instance, it may be employed in connection with apparatus of the kind disclosed in the application of Philip T. Dodge, Serial No. 721,823, filed September 23, 1912, wherein a totally different effect is secured, 80 namely, the spacer is prevented from arriving in the line behind a subsequently released matrix. In the present case, the spacer is retarded and freed from the detaining means by the operation of the next 85 matrix key, while in the Dodge application it is freed only by the operation of the spacer key, which permits it to be held in reserve near the line.

The terms "line" and "the line" are used 90 herein, as usual in this art, to designate the matrix line composed or in course of composition.

Having described my invention, what I claim is:

1. In a line casting machine, the combination of spacers or justifiers, a magazine wherein they are stored, an assembler wherein the line is composed, and means for delivering the spacers to the line by two 100 steps, first, from the magazine to a point near the line, and second, from said point to the line.

2. In a machine of the class described the combination of a support wherein the line is 105 composed, a magazine to contain the spacers, means for delivering a spacer therefrom, and means for detaining it at a point between the magazine and the line.

3. In combination with the assembler N, 110 the spacer magazine J, means for releasing the spacers from the magazine, and means for detaining the spacers between the magazine and the assembler.

4. The combination of the spacer magazine, a device for releasing the spacers therefrom, and a secondary device to arrest and retain the spacers before they reach the line which is being assembled.

5. In a machine of the class described, the 120 combination of means to release individual spacers from their magazine and a finger-key to actuate such releasing device, means for arresting said spacers in advance of the line, means for releasing individual matrices 125 from their magazine, and a single finger-key arranged to activate the matrix-releasing device and to disengage the spacer-arresting device; whereby the first key transfers the spacer to a point near the line and 130

the second key delivers both the transferred spacer and a matrix to the line.

6. In a machine of the class described, the combination of spacers and means located near the line for delivering the spacers thereto, matrices located at a greater distance from the line and means for delivering the matrices thereto, and a single finger-key whereby said two delivering means are caused to operate simultaneously and thus to deliver the spacer to the line in advance of the matrix.

7. In a machine of the class described, means for delivering spacers to the line, a series of finger keys for delivering matrices to the line, and means connecting all said keys with the spacer-releasing mechanism.

8. In combination with the series of matrix-releasing escapements C, actuating

reeds, a spacer releasing device Q, and the 20 rocking frame connecting the actuating reeds with said device.

9. In a machine of the class described, matrix releasing devices, the finger keys connected therewith, the spacer releasing device and the finger key connected therewith, and intermediate connections whereby the matrix keys are caused to operate the spacer releasing-device, the spacer key being free to operate without affecting the matrix re- 25 30 leasing devices.

In testimony whereof I hereunto set my hand this 8th day of June, 1910, in the presence of two attesting witnesses.

HENRY ARCHIBALD ARMSTRONG.
